TABLE LIGHTER

Edward I. Klein, 45 Maiden Lane, Jericho, N.Y.
Filed Oct. 27, 1959, Ser. No. 848,959
11 Claims. (Cl. 67—4.1)

This invention relates, in general, to cigarette or cigar lighters and pertains, more particularly, to a device of this nature intended to be constructed in ornamental form.

Table lighters are normally provided with some sort of ornamental form or base and frequently incorporate triggering mechanisms which are of the quick-release type. That is to say, frequently ornamental table lighters are actuated by some means other than the conventional thumb wheel which is a common expedient with pocket lighters. Some means is usually employed which remotely actuates the flint wheel and this mechanism frequently is relatively complicated and expensive to manufacture. It is, therefore, of primary concern in connection with the present invention to provide a novel and improved construction for a table lighter in which the component parts of the lighter mechanism, and particularly the actuating mechanism therefor, are arranged in a novel manner which makes the mechanism relatively simple and economical to manufacture.

Another object of this invention is to provide improvements in ornamental table lighters in which the ornamental portion of the lighter or frame is provided with an integral unit which is complete in and of itself and which constitutes the actuating mechanism for the device.

Still another object of this invention resides in the provision of a lighter mechanism employing a mounting element upon which all of the component parts of the actuating mechanism are mounted and are related to effect the remote operation and actuation of a flint wheel for the purpose of producing a spark in the vicinity of a wick wetted by lighter fluid.

Another object of this invention is to provide a novel table lighter construction employing a mounting strap having integral parts and portions thereof deformed or bent relative to the main body portion thereof to provide mounting means for certain component parts of the mechanism as well as guides and cam actuating means therefor and which strap also forms a mount for a trigger mechanism pivotally attached thereto and depending therefrom, by means of which the mechanism may be actuated.

Still another object of this invention resides in the provision of a novel lighter mechanism incorporating a base plate or strap upon which all of the component parts of the mechanism are mounted and which component parts include various levers and links operatively mounted on and associated with the base plate or strap and wherein the mechanism also includes a flint wheel having an associated pawl and ratchet mechanism and a flint carrier for holding the flint against the wheel to produce the necessary spark for operation of the lighter.

Still another object of this invention resides in the use of a mounting plate or strap which is provided with an upstanding end portion which forms a means by which a flint carrying mechanism is attached thereto in generally horizontally extending attitude and with there being a flint wheel mounted on the strap adjacent such upstanding end for cooperation with the flint carrier and with the mounting member or strap further carrying a trigger mechanism and associated levers and links for spinning the flint wheel in response to actuation of the trigger mechanism.

Another object of this invention is to provide a mechanism in accordance with the preceding object wherein the

2

opposite end of the mounting strap is also provided with an upstanding portion which is provided with slots or apertures, one of which provides a guide for a rack member which is engageable with the flint wheel assembly to spin the same and another of which is cooperable with a rack actuating and release mechanism and guides the same and cooperates therewith to produce a camming action thereon for releasing the rack in proper relationship so as to effect the spinning of the flint wheel.

10 A further object of this invention is to provide a mechanism in accordance with the preceding object wherein the mounting strap is secured to a base of ornamental character and which carries a hollow post through which a wick is extended, one side of the post being notched 15 to form a guide for the forward end of the rack closely adjacent to the flint wheel.

As this invention may be embodied in several forms without departing from the spirit or essential characteristics thereof, the present embodiment is therefore illustrative and not restrictive, and since the scope of the invention is defined by the appended claims, all changes that fall within the metes and bounds of the claims or that form their functional as well as conjointly cooperative equivalents are therefore intended to be embraced 25 by those claims.

In the drawings:

FIG. 1 is a side elevational view showing an ornamental table lighter constructed in accordance with this invention;

30 FIG. 2 is a top plan view of the assemblage shown in FIG. 1, with portions of the lighter being broken away to show the internal working parts thereof and their relative positioning with respect to each other;

FIG. 3 is a side elevational view, partly in section, illustrating the internal components of the lighter mechanism and showing the components in the normal or at rest position;

35 FIG. 4 is a view similar to FIG. 3 but showing the working components in position during the actuation of the lighter but just prior to completion of the actuation;

40 FIG. 5 is a sectional view showing the release mechanism just after the completion of the actuation cycle;

FIG. 6 is a transverse sectional view taken substantially along the plane of section line 5—5 in FIG. 2 and showing details of the flint wheel and its associated ratchet mechanism and illustrating relative positioning of the component parts;

45 FIG. 7 is a side elevational view of the actuating mechanism removed from the lighter;

50 FIG. 8 is an enlarged transverse section taken substantially along the plane of section line 8—8 in FIG. 7 and illustrating further details of the construction of the component parts; and

55 FIG. 9 is an enlarged vertical section taken substantially along the plane of section line 9—9 in FIG. 7, showing further details of the construction of the component parts of the actuating mechanism.

Referring at this time more particularly to FIG. 1, the reference numeral 10 designates, in general, a table lighter which, in the particular instance shown, is made generally in the form of a flint lock pistol, as will be clearly evident. The lighter includes a hand grip portion 11 which is connected directly to the main body portion 12 having a trigger guard 13 and the forward portion of the pistol includes a depending portion 14 which, in actuality is a reservoir for containing a quantity of lighter fluid, as more fully described hereinafter. The lighter also includes a hammer 15 and has a portion 16 simulating the powder pan of a flint lock pistol which is normally covered by the hinged cover member 17.

At the fore portion of the lighter, there is provided a stand 18 which, as can be seen from FIG. 1, serves to sup-

port the forward end of the lighter while the butt end of the handle 11 forms, with the stand, a complete support for the lighter.

The intermediate or receiver portion 20 of the lighter is hollow, being defined between the opposite side walls 21 and 22 of the lighter, see particularly FIG. 2, and bounded at the bottom by the bottom wall 23, see particularly FIG. 3, and being normally covered by a plate which carries the aforementioned hammer 15 and which plate extends along over the top of the handle 11 in the recessed portion 24. This cover plate, which is not shown, is provided with suitable apertures adjacent the opposite ends thereof, one of which receives a wood screw which may be screwed into the handle 11 which is preferably made of wood. An aperture is provided at the opposite end of the cover plate and a screw member is engaged therethrough and into the threaded upper end of a post 25, the purpose of which will be presently apparent.

The bottom wall 23 has a projection 26, see particularly FIG. 3, which extends rearwardly therefrom in accordance with the profile of the hand grip member 11 and is secured at its terminal end portion 27 thereto as by means of a wood screw 28 or the like.

The forward portion of the handle 11 is notched as indicated by the reference character 29, see particularly FIGS. 2 and 3, leaving opposite side portions 30 and 31 projecting forwardly therefrom. The reason for this notching is to provide clearance for the actuating mechanism which is indicated generally by the reference character 32 and whose operation will become presently apparent.

The frame for the lighter includes the aforementioned side walls 21 and 22 and the bottom wall 23 integral therewith, together with the trigger guard 13 which is integral with the bottom wall and the extension 26 likewise is integral with the frame. The forward portion of the frame beyond the bottom wall 23 and the trigger guard is formed of arcuate integral extensions 33 and 34 of the side walls 21 and 22 respectively and which extensions form the outer sides of the aforementioned pan 16. The forward ends of these extensions 33 and 34 are joined together by a forwardly projecting nose piece 35 which terminates at its forward end in the depending flange portion 36 whose outer face is stepped as shown most clearly in FIG. 3 and as indicated by the reference character 37 and receives the upper end of the stand 18, a suitable screw 38 being provided for securing the stand to this nose piece. Also integral with the nose piece is a pair of upstanding ears 39 and 40. All of the aforementioned elements and components are integrally formed preferably in a single casting or are otherwise rigidly joined together to form an integral and complete unit which constitutes the main frame for the ornamental table lighter.

The previously mentioned cover 17 is provided with a pair of forwardly extending hinge noses 41 and 42 notched as at 43, see particularly FIG. 3, on their undersides receiving the upper ends of the ears 39 and 40 and a pivot pin 44 projects through the ears and the noses to pivotally mount the cover upon the frame for the lighter and allow it to move between its normal position, such as shown in FIGS. 1 and 3, to a pivoted position such as is shown in FIG. 4. A further notch 50 is provided in the cover member 17, see particularly FIG. 6, which receives the forward end 51 of a cover actuating lever hereinafter more fully described and is pivotally attached thereto by means of a hinge pin 52 threaded as at 53 for securing to the cover member and for the purpose of securing pivotal attachment between the cover member and the lever portion 51.

The reservoir 14, see particularly FIG. 3, is engaged against the undersurface of the nose piece 35 and is rigidly affixed thereto as by means of the screw member 55. The rearward portion of the top wall 56 of the reservoir carries a hollow post 57 through which the wick 58 extends and by means of which the fluid contained within the reservoir is conveyed to a point closely adjacent to the

sparking mechanism of the lighter. As is conventional, the interior of the reservoir 14 is filled with a supply of absorbent material, such as cotton, as indicated by the reference character 59.

The actuating mechanism 32 is provided with a mounting base in the form of an elongate strap 60 having a forward portion bent upwardly as indicated by the reference character 61, see particularly FIG. 7, which then extends for a short distance in the horizontal portion 62 and terminates at the forward end in the upstanding flange portion 63. The intermediate portion of the strap is provided with an opening formed between two downturned ear portions 64 and 65, see particularly FIG. 8. Extending upwardly through this opening in the strap is the trigger 66 having an intermediate enlarged boss portion 67 provided with a transverse bore aligned with openings in the ears 64 and 65 and receiving therethrough the trigger pivot pin 68. The rearward end of the strap 60 is provided with an upturned flange portion 69 which is formed on one side thereof, see particularly FIG. 9, and the other side is formed with a narrow extension 70 which is slightly angulated upwardly from the main body portion of the strap and terminates in the hook end portion 71.

The upper end of the trigger 66 has an extension 75 which is apertured at its upper extremity and receives therethrough a transverse pivot pin 76 which has an enlarged head on one side of the extension and which projects laterally outwardly therefrom on the other side. This pivot pin is provided with an enlarged head portion 77 to hold it in place and on its laterally outwardly projecting end portion receives the end portions 78 and 79 of two different lever elements.

Interposed between these two lever end portions 78 and 79 is a torsion spring 80 having opposite end portions 81 and 82 extending therefrom and engaged with the respective levers 83 and 84. The lever 83 is that lever which includes the end portion 51 and is attached to the cover 17 and projects forwardly from the trigger 66, whereas the lever 84 is that which has its end portion 78 engaged with the pivot pin 76 and extends rearwardly from the trigger and passes through a notch 85 formed in the top edge 86 of the upstanding flange portion 69 of the strap 60.

The spring 80 is hooked over the lever 83 as at 87 and its opposite end portion 81 is engaged over the lateral end 88 on the lever 84. The net effect of the spring 80 and its connection to the levers 83 and 84 is to tend to urge these levers both downwardly at their free ends, or in other words, counterclockwise as regards the lever 84 and clockwise as regards the lever 83 as viewed in FIG. 7.

A rack bar 90 is positioned so as to extend through an opening in the upstanding flange 69 previously mentioned and to extend rearwardly therefrom to a point just short of the lateral tang 91 formed on the rear end of the lever 84, see particularly FIG. 2. On the forward side of the flange 69, the rack bar is of greater width than it is on the rearward side thereof so as to form a stop shoulder engaging with the forward face of the upstanding flange 69 and thus limit the rearward movement of the rack bar. The rack bar itself is provided with an aperture intermediate its ends and forwardly of the flange 69 through which one end portion 100 of a tension spring 101 is engaged, the opposite end 102 of this spring being hooked through an aperture 103 in the flange 69 and serving normally to urge the stop shoulder 104 previously described into engagement with the forward face of the flange 69. The stop shoulder 104 can be viewed in FIG. 4.

The release lever 84 is downturned in its rearward end portion 105 and the lower edge 106 thereof forms a cam surface cooperable with the notch 85 in the flange 69. As the trigger is pulled in the normal manner, as is shown in FIG. 4, the extension 75 thereof will move the release lever 84 forwardly and will also move the cover lever 83 forwardly. The tang 91 on the release lever, being engaged with the rearward end of the rack bar, moves

this rack bar forwardly also against the action of the spring 101 until such time as the cam edge 106 has moved to a position substantially as shown in FIG. 5 so as to raise the tang 91 out of engagement with the rack bar 90 and to thus cause its release and permit the spring 101 to rapidly return it to its normal position of rest wherein the shoulders 104 are engaged with the forward face of the upstanding flange 69.

The forward end of the rack bar on the inner edge thereof is provided with teeth 110 which are engageable with a gear 111 which forms part of the spark making mechanism. The gear is rotatably mounted on a vertical pivot pin 112 and mounted immediately above the gear is a pawl spring 113 having one downturned end portion 114 securing engagement with the gear and having an angulated opposite end portion 115 engageable with the ratchet teeth 116 formed in the undersurface of the flint wheel 117. The flint wheel 117, the pawl member 113 and the gear 111 are of entirely conventional construction. The pivot pin 112 is received at its lower end in the portion 62 of the strap 60 and at its upper end in the rearward extension 118 of a flint receiving barrel 120. The barrel 120 is rigidly affixed to the upstanding flange portion 63 of the strap 60 and has a reduced forward end portion 121 extending therebeyond. The barrel 120 and, of course, its extension 121 are provided with a longitudinal bore through which the flint is projected under the action of a suitable spring for engagement with the flint wheel 117. An adjusting screw 122, see particularly FIG. 4, is threadedly engaged in the extension 121 and may be adjusted to decrease or increase the tension of the spring urging the flint against the flint wheel.

The previously mentioned post 57 which carries the wick 58 is notched on one side, see particularly FIG. 6, as indicated by the reference character 130, this notch guiding and receiving the forward end portion of the rack bar 90 and serving to maintain the teeth 110 in mesh with the gear 111.

A further spring 131 is provided in the actuating mechanism having its opposite ends respectively connected to the upstanding portion 71 at the rear of the strap 60 and to a portion of the lever 83. The spring 131 serves the purpose of returning the cover rapidly to its initial position, that is its closed position, at the end of the cycle of operations of the device. The lever 83, of course, serves to slowly open the cover 17 as the trigger is pulled and when the release lever 84 has been disengaged from the rack bar 90, the trigger can then be released and the spring 131 will return not only the cover 17 but also the two levers on the trigger 66 to their normal or at rest positions. As the rack bar is moved forwardly, during the initial operation, the gear 111 will be rotated but since the direction of rotation is such as to cause lost motion of the ratchet mechanism, the flint wheel 117 will not move. However, as soon as the release lever has been disengaged from the rack bar, the rack bar under the action of the spring 101, will rapidly return to its initial position and will spin the gear 111 in the opposite direction and will, consequently, through the pawl and ratchet mechanism spin the flint wheel 117 which produces a spark igniting the fluid contained within the exposed upper end 140 of wick 58.

Thus, it will be evident that the actuating mechanism forms a separate and distinct entity complete in and of itself, which is mounted within the receiver portion of the lighter. The previously mentioned post 25, as can be seen better in FIG. 4, has a reduced lower end portion 141 which is threaded and which serves, in part, to fasten the actuating mechanism, and more particularly, the strap 60 thereof to the frame. A further screw 142 is also projected through the strap and these two screw members together form the means by which the actuating mechanism is rigidly affixed within the lighter frame. The reservoir member is separate as is the actuating mechanism and these two components together with the frame

form the principal operating parts of the lighter assembly.

I claim:

1. An actuating mechanism for lighters comprising an elongate mounting base having a flint wheel and associated ratchet mechanism mounted on one end thereof, the opposite end of said mounting base having an upstanding portion, said upstanding portion having a notch formed in its upper edge and an aperture therethrough below the slot, an elongate rack bar having one end reciprocably received in said aperture in the upstanding portion and being guided thereby and having its opposite end provided with rack teeth engaged with said ratchet mechanism whereby reciprocation of said rack bar will effect operation of said flint wheel, guide means engaging said opposite end of said rack bar for guiding the rack teeth into operative relationship with the ratchet mechanism, spring means normally urging said rack bar in a direction toward the opposite end of said mounting base, an actuating lever having an intermediate portion received in said notch in the upstanding portion of the mounting base and being guided thereby, said actuating lever having a downturned end portion beyond said upstanding portion presenting a lower edge portion thereof effecting a cam surface and terminating at such end in a laterally extending ear engageable with one end of said rack bar, means for effecting forward movement of said actuating lever toward said flint wheel to correspondingly urge said rack bar forwardly until said cam surface lifts said actuating lever out of engagement with the rack bar for return movement under the action of said spring means.

2. In a table lighter having a frame and including a reservoir provided with an upstanding hollow post for receiving a wick therethrough, a mounting base fixed to said frame and having one end portion overlying said reservoir to one side of said post, a flint wheel and ratchet mechanism fixed to said mounting base adjacent said post, said mounting base having an upstanding portion at its opposite end, said upstanding portion being provided with an aperture therethrough and a notch at its upper end, a rack bar having one end slidably received in said aperture and having its opposite end provided with teeth on one side thereof engaging said ratchet mechanism and said post having a notch facing said ratchet mechanism and receiving the opposite side of said rack bar, spring means normally urging said rack bar to one extreme position relative to said mounting means and said ratchet mechanism, and link means including a portion extending through said notch and guided thereby for moving said rack bar towards its other extreme position and including cam mechanism for suddenly releasing said rack bar as it reaches its other extreme position.

3. In a table lighter having a frame and including a reservoir provided with an upstanding hollow post for receiving a wick therethrough, a mounting base fixed to said frame and having one end portion overlying said reservoir to one side of said post, a flint wheel and ratchet mechanism fixed to said mounting base adjacent said post, said mounting base having an upstanding portion at its opposite end, said upstanding portion being provided with an aperture therethrough and a notch at its upper end, a rack bar having one end slidably received in said aperture and having its opposite end provided with teeth on one side thereof engaging said ratchet mechanism and said post having a notch facing said ratchet mechanism and receiving the opposite side of said rack bar, spring means normally urging said rack bar to one extreme position relative to said mounting base and said ratchet mechanism, link means for moving said rack bar towards its other extreme position and including cam mechanism for suddenly releasing said rack bar as it reaches its other extreme position, said link means including a portion guided by said notch in the upstanding portion of said mounting base and having an arcuate undersurface effecting the camming action to release said rack bar.

4. In a table lighter having a frame and including a reservoir provided with an upstanding hollow post for receiving a wick therethrough, a mounting base fixed to said frame and having one end portion overlying said reservoir to one side of said post, a flint wheel and ratchet mechanism fixed to said mounting base adjacent said post, said mounting base having an upstanding portion at its opposite end, said upstanding portion being provided with an aperture therethrough and a notch at its upper end, a rack bar having one end slidably received in said aperture and having its opposite end provided with teeth on one side thereof engaging said ratchet mechanism and said post having a notch facing said ratchet mechanism and receiving the opposite side of said rack bar, spring means normally urging said rack bar to one extreme position relative to said mounting base and said ratchet mechanism, and link means including a portion extending through said notch and guided thereby for moving said rack bar towards its other extreme position and including cam mechanism for suddenly releasing said rack bar as it reaches its other extreme position, said one end of the mounting base having an upstanding portion beyond said flint wheel and ratchet mechanism, and a flint carrier fixed to said last mentioned upstanding portion of the mounting base and including means for biasing a flint into engagement with said flint wheel.

5. In a table lighter having a frame and including a reservoir provided with an upstanding hollow post for receiving a wick therethrough, a mounting base fixed to said frame and having one end portion overlying said reservoir to one side of said post, a flint wheel and ratchet mechanism fixed to said mounting base adjacent said post, said mounting base having an upstanding portion at its opposite end, said upstanding portion being provided with an aperture therethrough and a notch at its upper end, a rack bar having one end slidably received in said aperture and having its opposite end provided with teeth on one side thereof engaging said ratchet mechanism and said post having a notch facing said ratchet mechanism and receiving the opposite side of said rack bar, spring means normally urging said rack bar to one extreme position relative to said mounting means and said ratchet mechanism, link means for moving said rack bar towards its other extreme position and including cam mechanism for suddenly releasing said rack bar as it reaches its other extreme position, said link means including a portion guided by said notch in the upstanding portion of said mounting base and having an arcuate undersurface effecting the camming action to release said rack bar, said one end of the mounting base having an upstanding portion beyond said flint wheel and ratchet mechanism, and a flint carrier fixed to said last mentioned upstanding portion of the mounting base and including means for biasing a flint into engagement with said flint wheel.

6. An ornamental lighter comprising a frame of ornamental configuration and including a bottom wall and opposite side walls, a mounting base fixed to said bottom wall and being enclosed by said side walls, a flint wheel and associated ratchet mechanism fixed to one end of said mounting base, a fuel reservoir fixed to the underside of said frame and including an upstanding hollow post for receiving a wick therethrough and being disposed to one side of but closely adjacent to said flint wheel, a rack bar extending along said mounting base and having teeth at one end engaging said ratchet mechanism, spring means normally urging said rack bar to an axial extreme position, link means for moving said rack bar in opposition to said spring means and including cam release mechanism for suddenly releasing said rack bar for return movement thereof under the action of said spring means, the end of said mounting base opposite said one end thereof upon which the flint wheel is mounted having an upstanding portion including an aperture therein, one end of said rack bar being guidably received within

5 said aperture in said upstanding portion, said link means including an elongate link having an intermediate portion received in a notch in the top edge of said upstanding portion and being guided thereby and having one end downwardly arcuated to define along its lower edge a cam surface cooperable with the notch to effect the camming action aforementioned, and such link terminating in a laterally directed end portion engageable with a corresponding end of said rack bar.

10 7. In a table lighter having a frame, a reservoir and an upstanding hollow post for receiving a wick therethrough being supported by said frame, a mounting base fixed to said frame and having one end portion disposed adjacent to one side of said post, a flint wheel and ratchet mechanism fixed to said mounting base adjacent said post, said mounting base having an upstanding portion at its opposite end, said upstanding portion being provided with an aperture therethrough and a notch at its upper end, a rack bar having one end slidably received 15 in said aperture and having its opposite end provided with teeth on one side thereof engaging said ratchet mechanism and said post having a notch facing said ratchet mechanism and receiving the opposite side of said rack bar, spring means normally urging said rack bar to one 20 extreme position relative to said mounting means and said ratchet mechanism, and link means including a portion extending through said notch and guided thereby for moving said rack bar towards its other extreme position and including cam mechanism for suddenly releasing said 25 rack bar as it reaches its other extreme position.

30 8. In a table lighter having a frame, a reservoir and an upstanding hollow post for receiving a wick therethrough being supported by said frame, a mounting base fixed to said frame and having one end portion disposed 35 adjacent to one side of said post, a flint wheel and ratchet mechanism fixed to said mounting base adjacent said post, said mounting base having an upstanding portion at its opposite end, said upstanding portion being provided with an aperture therethrough and a notch at its upper end, a rack bar having one end slidably received 40 in said aperture and having its opposite end provided with teeth on one side thereof engaging said ratchet mechanism and said post having a notch facing said ratchet mechanism and receiving the opposite side of said 45 rack bar, spring means normally urging said rack bar to one extreme position relative to said mounting base and said ratchet mechanism, link means for moving said rack bar towards its other extreme position and including cam mechanism for suddenly releasing said rack bar as it reaches its other extreme position, said link means including a portion guided by said notch in the upstanding 50 portion of said mounting base and having an arcuate undersurface effecting the camming action to release said rack bar.

55 9. In a table lighter having a frame, a reservoir and an upstanding hollow post for receiving a wick therethrough being supported by said frame, a mounting base fixed to said frame and having one end portion disposed adjacent to one side of said post, a flint wheel and ratchet mechanism fixed to said mounting base adjacent said post, said mounting base having an upstanding portion at its opposite end, said upstanding portion being provided with an aperture therethrough and a notch at its upper end, a rack bar having one end slidably received 60 in said aperture and having its opposite end provided with teeth on one side thereof engaging said ratchet mechanism and said post having a notch facing said ratchet mechanism and receiving the opposite side of said rack bar, spring means normally urging said rack bar to one extreme position relative to said mounting base and said ratchet mechanism, and link means including a portion extending through said notch and guided thereby for moving said rack bar towards its other extreme position and including cam mechanism for suddenly releasing said rack 65 bar as it reaches its other extreme position.

70 10. In a table lighter having a frame, a reservoir and an upstanding hollow post for receiving a wick therethrough being supported by said frame, a mounting base fixed to said frame and having one end portion disposed adjacent to one side of said post, a flint wheel and ratchet mechanism fixed to said mounting base adjacent said post, said mounting base having an upstanding portion at its opposite end, said upstanding portion being provided with an aperture therethrough and a notch at its upper end, a rack bar having one end slidably received in said aperture and having its opposite end provided with teeth on one side thereof engaging said ratchet mechanism and said post having a notch facing said ratchet mechanism and receiving the opposite side of said rack bar, spring means normally urging said rack bar to one extreme position relative to said mounting base and said ratchet mechanism, and link means including a portion extending through said notch and guided thereby for moving said rack bar towards its other extreme position and including cam mechanism for suddenly releasing said rack bar as it reaches its other

extreme position, said one end of the mounting base having an upstanding portion beyond said flint wheel and ratchet mechanism, and a flint carrier fixed to said last mentioned upstanding portion of the mounting base and including means for biasing a flint into engagement with said flint wheel.

10. In a table lighter having a frame, a reservoir and an upstanding hollow post for receiving a wick therethrough being supported by said frame, a mounting base fixed to said frame and having one end portion disposed adjacent to one side of said post, a flint wheel and ratchet mechanism fixed to said mounting base adjacent said post, said mounting base having an upstanding portion at its opposite end, said upstanding portion being provided with an aperture therethrough and a notch at its upper end, a rack bar having one end slidably received in said aperture and having its opposite end provided with teeth on one side thereof engaging said ratchet mechanism and said post having a notch facing said ratchet mechanism and receiving the opposite side of said rack bar, spring means normally urging said rack bar to one extreme position relative to said mounting means and said ratchet mechanism, link means for moving said rack bar towards its other extreme position and including cam mechanism for suddenly releasing said rack bar as it reaches its other extreme position, said link means including a portion guided by said notch in the upstanding portion of said mounting base and having an arcuate undersurface effecting the camming action to release said rack bar, said one end of the mounting base having an upstanding portion beyond said flint wheel and ratchet mechanism, and a flint carrier fixed to said last-mentioned upstanding portion of the mounting base and including means for biasing a flint into engagement with said flint wheel.

11. An ornamental lighter comprising a frame of ornamental configuration and including a bottom wall and

opposite side walls, a mounting base fixed to said bottom wall and being enclosed by said side walls, a flint wheel and associated ratchet mechanism fixed to one end of said mounting base, a fuel reservoir and an upstanding hollow post for receiving a wick therethrough being supported by said frame, said post being disposed to one side of but closely adjacent to said flint wheel, a rack bar extending along said mounting base and having teeth at one end engaging said ratchet mechanism, spring means normally urging said rack bar to an axial extreme position, link means for moving said rack bar in opposition to said spring means and including cam release mechanism for suddenly releasing said rack bar for return movement thereof under the action of said spring means, the end of said mounting base opposite said one end thereof upon which the flint wheel is mounted having an upstanding portion including an aperture therein, said upstanding portion having a notch formed in the top edge thereof, one end of said rack bar being guidably received within said aperture in said upstanding portion, said link means including an elongate link having an intermediate portion received in said notch and being guided thereby and having one end downwardly arcuated to define along its lower edge a cam surface cooperable with the notch to effect the camming action aforementioned, and such link terminating in a laterally directed end portion engageable with a corresponding end of said rack bar.
